UNITED STATES PATENT OFFICE

ISRAEL C. ORSWELL, OF MEDFORD, MASSACHUSETTS, ASSIGNOR TO THE AMRAD CORPORATION, OF MEDFORD, MASSACHUSETTS, A CORPORATION OF OHIO

ELECTRICAL TUBE

Application filed June 23, 1926, Serial No. 117,991. Renewed February 26, 1930.

The present invention relates to electrical tubes and more particularly to tubes operating through space conduction of electrical currents. Tubes of this general character are of two types, the thermionic tube which operates through emission of electrons from a hot filament or cathode and the gaseous conduction tube which operates by ionization of molecules in a gaseous medium.

One object of the invention is to provide a rectifier tube operating upon the principles of gaseous conduction by which there is obtained a high efficiency of rectification and a uniform discharge over long periods of time. Another object of the present invention is to improve the construction of electrical tubes particularly with a view to providing a tube of rigid and durable construction in which the electrodes are supported in a manner to be unaffected by mechanical stresses and to resist breakdown due to electrical discharges.

With the above and other objects in view as will hereinafter appear, one feature of the invention comprises a gaseous conduction tube having a cathode member of large internal surface surrounding an anode of comparatively small dimensions received within the cathode member, the electrodes being immersed in a rarefied gaseous medium. With this construction, the tube possesses the property of unilateral conductivity, the current passing freely from the anode to the cathode, but not to an appreciable extent in the reverse direction. The construction of the present invention is such that considerable area for conduction at the surfaces of the electrodes is provided so that high current conduction without excessive heating or unduly large voltage drops is obtained. In the preferred form of the invention, the tube is constructed to give full wave rectification, the cathode member for this purpose being divided into two parts by a central shield or baffle plate and the anodes being received in the opposite portions of the cathode member. The baffle plate forms an effective portion of the cathode surface and by being extended beyond the anodes prevents undue electric discharge between the two anodes which are

necessarily maintained at a high potential difference.

A further feature of the invention consists in improved means for supporting the electrodes which may be employed for any type of tube, whether operating by gaseous ionization or by emission of electrons from a filament. The envelope is provided with a re-entrant stem having at its upper end a press formed with a plurality of angularly disposed wings within which the lead-in wires and the supports for the electrodes are sealed. This angular arrangement of the wings provides for a rigid support of the electrodes at a number of spaced points, which not only assures a high resistance to deformation under mechanical stresses such as may be encountered in transit or in ordinary use of the tube, but also permits mounting of the electrodes in a manner to localize the discharge, so that breakdown and non-uniform action are effectively prevented.

Still further features of the invention consist in certain novel features of construction, combinations and arrangements of parts hereinafter described and particularly defined in the claims.

In the accompanying drawings, Fig. 1 is a vertical elevation, partly in section, of a gaseous conduction tube embodying the several features of the present invention; Fig. 2 is a section on line 2—2 of Fig. 1; and Fig. 3 is a section on line 3—3 of Fig. 1.

The illustrated embodiment of the invention comprises a gaseous conduction tube adapted to give full wave rectification when connected into a suitable energizing circuit. The tube comprises a cathode and two anodes immersed in a gas which is preferably an inert gas such as helium under pressure of the order of magnitude of ten millimeters. The cathode member as shown is of cylindrical formation, being divided by a shield or baffle plate to form two cathode surfaces, and the two anodes are received within the two portions of the cathode, the entire assembly being supported upon a stem which is formed in a manner to give high mechanical rigidity and which is not affected by electrical stresses within the tube.

Referring particularly to the drawings, the illustrated tube consists of a cathode member 2 which is of cylindrical formation, its ends being joined by a seam indicated at 4. Cooperating with the cathode member are two anodes 6 and 8 which are rod shaped and of materially less surface area than the cathode member. The anodes are received within the cathode member, and protection against unduly large discharges directly between the anodes is afforded by a shield or baffle plate 10 which forms a part of the cathode member and which is welded thereto at opposite sides. The shield divides the cathode member into two semi-cylindrical cathodes and forms a portion of the cathode surface of each. The shield is of greater length than the cylindrical cathode member and extends considerably above the upper extremities of the anodes so that the paths for electric discharge directly between the anodes are long. Any discharge which takes place between the anodes, therefore, is unappreciable and does not materially affect the operation of the tube. The electrodes are of nickel, which has high heat resisting properties, and are immersed in a rarefied atmosphere of helium or other inert gas contained in a sealed envelope 12. The electrodes are supported in the following manner: Connected with the envelope 12 at the bottom thereof is a re-entrant stem 14 which is formed at its upper end with a press indicated generally at 16. This press is formed with four wings 18 of solid glass which extend at right angles to each other and which are of enlarged cross section at their outer extremities, as indicated at 20 in Fig. 3. The wings are also enlarged along their upper surfaces indicated at 22 in Fig. 1. These enlarged surfaces 22 constitute a thickened ledge which appears at 24 in Fig. 2. At the outer extremities of each wing is sealed a supporting bracket 26 of wire which is of such form as to engage with the lower part of the cathode member 2. The cathode member is welded to each of the bracket wires. The anodes 6 and 8 extend through glass tubes 28 and 30 respectively, which are formed integrally with the stem, the anode wires themselves being sealed into the upper ledge portion 24 of the stem. In order to protect the glass tubes from discharges due to the electrical stresses between the electrodes, the tubes are fitted with bushings 32 and 34 which are of lava or other insulating material. Each bushing has a recess which fits closely over its cooperating glass tube and has at its upper end a central opening through which the anode wire extends. After fitting of the bushings around the anodes, the latter are bent as indicated at 38 in order to retain the bushings firmly thereon. It will be seen that the shield 10 extends for a slight distance below the bottom ends of the

bushings in order to protect the latter from the electric fields which are set up between the two anodes.

Electrical connections to the external circuits are made through lead wires 40 and 42 which connect to the anodes and a wire 44 which connects with the cathode member. The lead wires 40 and 42 are welded to the lower ends of the anode wires before being sealed into the stem and the wire 44 is similarly welded to one of the supporting wires 26. The lead wires, as well as the supporting wires 26, are preferably of copper-clad iron which may be conveniently welded to the nickel electrodes and which form a tight seal in cooperation with the glass stem. The envelope is cemented to a base 46 which has a plurality of contact pins 48 to which the various lead wires are soldered, as indicated in Fig. 1. The construction of the base and its associated contact pins is such as to permit engagement of the tube in any standard vacuum tube socket.

The steps in the manufacture of the tube are briefly described as follows: The stem 14 of hollow cylindrical construction is first formed with a flare 50 at its lower end to afford connection to the envelope 12. The stem is then suitably mounted for heating, at which time the anode supporting tubes 28 and 30 are pressed in engagement with the stem while the supporting wires 26 for the cathode member and the anode wires 6 and 8 with their corresponding lead wires are pressed in the proper position. The upper end of the stem is then heated and is crimped to form the wings of the press, this action serving to unite the tubes 28 and 30 with the press and at the same time to seal the various wires into the glass. The lava bushings are then mounted on the anodes and the anodes are bent as at 38 to retain the bushings in proper position. Next the cathode cylinder is mounted on and welded to the supporting bracket wires 26. The envelope 12 is then sealed to the stem in the usual manner as the tube is exhausted through the tip 52. As exhaustion proceeds, the cathode member 2 is intensely heated by an induced high frequency current to drive off any occluded gas. This heating is preferably carried to a point where the cathode member becomes white hot. After the tube has been thus exhausted and is permitted to cool, the desired amount of inert gas is admitted, whereupon the tube is sealed at the tip. The tube is then mounted on the base, the lead wires being soldered into the contact pins.

The supporting structure for the electrodes is applicable not only to a tube of the gaseous conduction type as illustrated and described above, but may be used for supporting the electrodes in a tube of any character, as for example a tube of the thermionic type. The formation of the press, with angularly

disposed reinforced wings, presents high mechanical strength, which resists mechanical stresses applied in any direction. This stem, together with the supporting brackets for the cathode, forms a rigid and durable structure which assures against deformation or relative displacement of the electrodes through stresses incident to handling or use of the tube. In the preferred form, the construction is such that electrical discharges are largely confined to the interior of the cathode member so that the possibility of continued discharges immediately adjacent to the walls of the tube or of the stem are effectively prevented. The tube, therefore, is one of long life and uniform action, unaffected by either mechanical or electrical stresses which may be encountered in ordinary use.

Having thus described the invention, what is claimed is:

1. An electrical tube comprising an envelope, electrodes, and a re-entrant stem formed with a press having a plurality of angularly disposed wings and a substantially flat top portion connecting and surmounting the wings, supporting means for the electrodes and lead-in wires sealed in the press.

2. A rectifier tube comprising an envelope containing a gaseous medium, a cylindrical cathode member, an anode, a re-entrant stem formed at its upper end with a press having a plurality of wings disposed at substantially right angles to each other and having a flat ledge portion surmounting the wings, a plurality of supporting members for the cathode sealed in the wings, and lead-in wires to the cathode and anode sealed in the press.

3. A rectifier tube comprising an envelope, a re-entrant stem formed with a press having a plurality of angularly disposed wings, anode tubes formed integrally with the stem, cathode supporting members sealed in the wings of the press, a cathode mounted on the cathode supporting members, anodes extending through the anode tubes, and lead-in wires connected with the electrodes and sealed in the press.

In testimony whereof I have signed my name to this specification.

ISRAEL C. ORSWELL.
